(57) **CLAIM**

The ornamental design for an air fryer and accessory as shown and described.

DESCRIPTION

FIG. 1 is a perspective view of an air fryer of the present invention;

FIG. 2 is front view of the invention shown in FIG. 1;

FIG. 3 is rear view of the invention shown in FIG. 1;

FIG. 4 is a left-side view of the invention shown in FIG. 1;

FIG. 5 is a right-side view of the invention shown in FIG. 1;

FIG. 6 is a top view of the invention shown in FIG. 1;

FIG. 7 is a bottom view of the invention shown in FIG. 1;

FIG. 8 is a perspective view of a second embodiment of the air fryer of the present invention;

FIG. 9 is front view of the invention shown in FIG. 8;

FIG. 10 is rear view of the invention shown in FIG. 8;

FIG. 11 is a left-side view of the invention shown in FIG. 8;

FIG. 12 is a right-side view of the invention shown in FIG. 8;

FIG. 13 is a top view of the invention shown in FIG. 8;

FIG. 14 is a bottom view of the invention shown in FIG. 8;

FIG. 15 is a perspective view of an accessory of an air fryer of the present invention;

FIG. 16 is front view of the invention shown in FIG. 15;

FIG. 17 is rear view of the invention shown in FIG. 15;

FIG. 18 is a left side view of the invention shown in FIG. 15;

FIG. 19 is a right side view of the invention shown in FIG. 15;

FIG. 20 is a top view of the invention shown in FIG. 15; and,

FIG. 21 is a bottom view of the invention shown in FIG. 15.

The invention is an air fryer and accessory, specifically, embodiments of the air fryer are illustrated in FIGS. 1–14 and the respective accessory, a basket, is shown in FIGS. 15–21. FIGS. 1–7 illustrate an air fryer having a transparent portion. Contour lines shown in the various views depict curvature, flatness, etc.
